Topeka, Kans.

Application August 1, 1940, Serial No. 349,318

11 Claims. (Cl. 37—129)

Our invention relates to improvements in scrapers designed for grading, road scraping and the like, and adapted for scraping up a load, carrying the load to a selected place and there dumping it.

One of the objects of our invention is to provide a novel scraper of the kind described comprising carrying means, draft means, a bowl having an open bottom and front, rear and side walls, a bottom member in the bowl having a front scraping edge, pivoted on a transverse axis to the draft means and pivoted on a transverse axis to swing from a lowered scraping position at its front edge to a load carrying position closing the open bottom of the bowl, and thence upwardly to a rearwardly facing dumping position, the bowl being pivotally supported on the bottom member on an axis parallel with the other two axes, so as to be bodily lifted when the bottom member swings from the scraping to the dumping position.

Our invention further provides novel means for swinging the bowl to raise its front wall when the bottom member swings from the scraping to the load carrying position, and for raising its rear wall when the bottom member swings from the load carrying to the dumping position.

Our invention provides the bowl under its front wall with a passage for the entrance of scraped material, and novel means for closing the passage when the bowl and bottom member are in the load carrying position, said closure means providing for the passage being left open when the bowl and bottom member are in the scraping and the dumping positions.

A further object of our invention is the provision of a novel scraper of the kind described, which is relatively simple in construction, strong, durable, not likely to get out of order, which is easily operated, and which is efficient in its operation.

The novel features of our invention are hereinafter fully described and claimed.

In the accompanying drawings which illustrate the preferred embodiment of our invention,

Fig. 1 is a side elevation, partly broken away, of the scraper, showing the bottom member in the scraping position, and the bowl lowered at its front wall to receive the scraped material through the passage thereunder, the closure being shown in an open position.

Fig. 2 is a side elevation, partly broken away, of the scraper, showing the bowl and the bottom member in the load carrying position, with the

front wall of the bowl raised to permit the closure to close the passage, as shown.

Fig. 3 is a side elevation, partly broken away, of the scraper, showing the bottom member in the dumping position, the closure in the open position, and the bowl bodily lifted and its rear wall raised.

Fig. 4 is a side elevation of the bowl.

Fig. 5 is a side elevation of the bottom scraper member, its integral triangular parts being omitted, and a part broken away.

Fig. 6 is a side elevation of the closure for the passage.

Fig. 7 is a plan view of the scraper shown in the load carrying position, with the bottom member closing the open bottom of the bowl, and the closure in the closed position.

Fig. 8 is a plan view, partly broken away, of the scraper, showing the bowl and bottom member in the dumping positions, the passage being shown uncovered by the closure.

Similar characters of reference designate similar parts in the different views.

The scraper is provided with draft means comprising, as shown in Figs. 1 to 3, 7 and 8, a frame consisting of a longitudinal tongue 1 the rear end of which is integral with a transverse member 2 from the ends of which respectively extend rearwardly two parallel arms 3. The front end 10 of the tongue 1 is adapted to be attached to a tractor, or other wise drawn, as by draft animals.

Located between the arms 3 of the draft frame is a load carrying bowl, designated generally by 4, which bowl has an open bottom, is rectangular in plan, has a concavo-convex front wall 5, a concavo-convex rear wall 6, and flat vertical side walls 7. The inner sides of the front and rear walls are concave.

For scraping material into the bowl 4 through its open bottom, and for closing its open bottom so that the load may be carried, there is provided a bottom scraper member 8 disposed in the bowl, having a front scraping edge 9 and upwardly extending side walls 10.

For pivotally supporting the bowl 4 on a transverse axis on the bottom member, there are two transversely aligned pivot pins 11 which respectively extend through and are rigidly secured to the walls 10 adjacent to the upper edges thereof and midway between the front and rear ends 50 of the bottom member 8. The pins 11 respectively extend outwardly through the side walls 7 of the bowl, substantially midway between the front wall 5 and rear wall 6 thereof, and pivotally support the bowl on a transverse horizontal

axis, so that the bowl can swing upwardly and downwardly at its front and rear walls.

The bottom member 8 is composed of two plates, one of which overlies the other and between and to which is rigidly fastened a transverse horizontal shaft 12 having projecting ends which are respectively pivoted in the draft arms 3 adjacent to the rear ends of the arms which the shaft 12 supports.

At the outer side of the bowl 4, at opposite sides thereof are two pairs of triangular plates 13 spaced apart and disposed vertically, and through which respectively extend, and are rigidly integrally secured, the ends of the shaft 12. The pins 11 are also respectively extended through and rigidly secured to the two pairs of triangular plates 13, whereby said plates become integral parts of and move with the bottom member 8.

Carrying means comprising, as shown, two wheels 14 are provided, which wheels are respectively rotatable on and support two transverse spindles 15 which respectively extend through and are integrally fastened to the two pairs of triangular plates 13. The spindles 15 serve as an axis on which the bottom member 8 is adapted to oscillate, so as to swing from the scraping position, shown in Fig. 1, to the load carrying position, shown in Figs. 2 and 7, and then upwardly to the dumping position shown in Figs. 3 and 8.

Means for oscillating the bottom member 8 on its axis, the spindles 15, comprise two piston rods 16 one set of ends of which are pivoted to the pins 11 respectively between the adjacent triangular plates 13, the other ends of the rods 16 being respectively fastened to two piston heads 17 respectively reciprocative in two longitudinally disposed cylinders 18, the front end of which are pivoted to two transverse pins 19 respectively mounted in two pairs of upstanding projections 20 on the upper side of the ends of the cross member 2 of the draft frame. Each cylinder 18 is provided at opposite sides respectively of the piston head 17 therein, with two pipes 21, connected to a suitable pressure fluid supply means, not shown, by which the pistons 16-17 are simultaneously reciprocated in the same direction.

When the piston heads 17 move rearwardly from the forward position, shown in Fig. 1, to the rear position, shown in Fig. 3, the bottom member 8 will be swung from the scraping position, Fig. 1, to the dumping position, Fig. 3, and when the piston heads move forwardly the bottom member 8 will be retracted to the scraping position.

The bowl 4 under the front wall 5 has a passage 22 for the entrance of material when the bottom member 8 is in the scraping position, shown in Fig. 1. For closing this passage 22 when the bottom member 8 has risen to the load carrying position, shown in Figs. 2 and 7, there is provided a U shaped closure 23 having a concavo-convex wall at the outer side of the front wall 5, and having two rearwardly extending arms 24, pivoted by two pins 25 respectively to the sides 7 of the bowl a short distance above the pins 11. The closure 23-24 is adapted to swing downwardly at its front end by gravity to a position in which it can close the passage 22, when the bowl 4 and bottom member 8 are in the load carrying position, shown in Figs. 2 and 7.

For supporting the closure 23-24 in the open position when the bottom member 8 is in the scraping position, shown in Fig. 1, and in the closed position when the bottom member is in

the load carrying position, shown in Figs. 2 and 7, each arm 24 of the closure has at its lower edge an outwardly extending flange 26. The flanges 26 respectively rest upon two inwardly extending rollers 27 mounted respectively on the inner sides of the arms 3 of the draft frame.

To support the closure 23-24 in the open position, when the bottom member 8 and bowl 4 are in the dumping position, shown in Figs. 3 and 8, two pins 28 are respectively mounted transversely in the two pairs of triangular plates 13 between the pins 11 and the shaft 12. When the bowl 4 and bottom member 8 are in the dumping position, shown in Figs. 3 and 8, the pins 15 28 will respectively engage the rear sides of the flanges 26, which extend upwardly at their rear end portions. The flanges 26 engage with the pins 28 just as the rollers 27 disengage with the flanges 26, as will be explained hereinafter.

Means are provided to swing the bowl 4 on its axis 11 to raise its front wall, when the bottom member swings from the scraping to the load carrying position, and for raising the rear wall of the bowl when the bottom member swings from the load carrying to the dumping position. The front and side walls 5 and 7 of the bowl are embraced by a U shaped fender 29, the side arms of which are above and cover the triangular plates 13 and parts adjacent thereto, so as to prevent dirt from falling between the plates. As shown in Figs. 2 and 3, the pins 11 extend through said side arms. Two forwardly extending arms 30 have their rear ends fastened rigidly to the front middle portion of the fender 29. Mounted in the forward ends of the arms 30 is a transverse pin 31 which extends through and travels in a longitudinal guiding slot 32 provided in a relatively thin longitudinal wall 33, which is integral with and extends upwardly from the tongue 1 of the draft frame.

The slot 32 from its front end extends upwardly and rearwardly, and thence downwardly and rearwardly. When the bottom member 8 is in the scraping position, shown in Fig. 1, the pin 31 will be, as shown, in the lower front end of the slot 32, and the front wall 5 of the bowl will be lowered, with the front lower edge portions of the side walls on the ground.

When the piston rods are forced rearwardly, they will swing the triangular plates 13 and the bottom member 8 counter-clockwise, as viewed in Figs. 1 and 2, thereby, due to the pivoting of the shaft 12 in the arms 3 of the draft frame, causing the wheels 14 to travel rearwardly, thus moving the bowl and bottom member bodily rearwardly. As the bowl moves rearwardly the pin 31 will travel upwardly in the slot 32, thus swinging the bowl on its axis 11 to raise the front wall to the load carrying position in which it and the bottom member will be held by the fluid operated power means, the pistons 16-17 and cylinders 18, until it is desired to dump the load. In Figs. 2 and 7, the parts are shown in the load carrying positions.

It will be noted that when the bottom member 8 is in the scraping position, and the front wall 5 of the bowl is lowered, as in Fig. 1, the rollers 27 support the flanges 26, holding the closure 23-24 in the open position, so material scraped

can pass through the passage 22 into the bowl 4. When the scraper bottom member 8 and the front wall 5 rise to the load carrying position, shown in Fig. 2, the rollers 27 will still support the flanges 26, holding the closure 23-24 in a position closing the passage 22, thus preventing

material passing downwardly through the passage 22 when the load is being carried to the dumping place.

When it is desired to dump the load, the operator causes the pressure fluid to force the pistons 16-17 further rearwardly, thus swinging the bottom member and its triangular plates further in a counterclockwise direction, as viewed in Fig. 3, and to the dumping position, shown in Fig. 3 and in Fig. 8. Such swinging of the bottom member 8 to the dumping position will bodily raise the bowl 4 upwardly and will further move the wheels 14 rearwardly, causing the rollers 27 to be disengaged from the flanges 26, at the same time causing the pins 28 to engage the rear side of the flanges 26 to hold the closure 23-24 in the open position, as shown in Fig. 3.

As the wheels 14 move rearwardly carrying the bowl 4 and bottom member rearwardly, the pin 31 will lower in the slot 32 from the elevated position shown in Fig. 2, and the pin will travel rearwardly to the rear end of the slot 32, as shown in Fig. 3, thus swinging the bowl 4 on its pivot pins 11 to raise the rear wall 7 of the bowl to the dumping position, shown in Fig. 3.

With the rear wall 7 of the bowl so raised, and the bottom member 8 in the rearwardly facing dumping position, and the closure 23-24 in the open position, the collected scraped material will be freely discharged from the bowl by gravity.

After dumping the load, and it is desired again to scrape up a load, the operator causes the fluid pressure to return the pistons 16-17 forwardly to their initial positions, shown in Fig. 1, thereby causing the bowl, bottom member and the other movable parts to reassume the positions shown in Fig. 1 thus completing a cycle of operations.

From the foregoing description, it will be noted that the bottom scraping member 8 is swung on its axis 12 by means independent of the bowl 4, the cylinders 18 pivoted to the draft frame transverse member 2, and the piston rods 16 pivoted to the triangular plates 13, integral portions of said bottom member.

It will also be noted that the bowl 4 is swung on its axis 11 by means of its arms 30 having traveling engagement with the slotted wall 33, which is integral with the tongue 1 of the draft frame.

Many modifications of our invention, within the scope of the appended claims may be made, without departing from the spirit of our invention.

What we claim is:

1. In a scraper, carrying means adapted for travel on the ground, a draft means, a bowl having an open bottom and front, rear and side walls, a bottom member in said bowl having a front scraping edge and pivoted to said draft means on a transverse axis and pivoted to said carrying means on an axis parallel with said axis, to swing upwardly at its front edge from a scraping position to, and past a load carrying position, to a rearwardly facing dumping position, means pivotally supporting said bowl on said bottom member on an axis parallel with said axes and disposed to bodily raise said bowl when said bottom member is swung upwardly at its front edge from a scraping to a dumping position, means connecting said bottom member with said draft means for so swinging said bottom member, and means for swinging said bowl to raise its front wall when said bottom member swings from a

scraping to a load carrying position and for swinging said bowl to raise its rear wall when said bottom member swings from the load carrying position to the dumping position.

5. 2. In a scraper, carrying means adapted for travel on the ground, a draft means, a bowl having an open bottom and front, rear and side walls and an arm extending forwardly from its front end, a bottom member in said bowl having a front scraping edge and pivoted to said draft means on a transverse axis and pivoted to said carrying means on an axis parallel with said axis, to swing upwardly at its front edge from a scraping position to, and past a load carrying position, to a rearwardly facing dumping position, means pivotally supporting said bowl on said bottom member on an axis parallel with said axes and disposed to bodily raise said bowl when said bottom member is swung upwardly at its front edge from a scraping to a dumping position, means independent of said bowl for so swinging said bottom member, and guiding means on said draft means with which said arm has traveling engagement for swinging said bowl to raise its front wall when said bottom member swings from a scraping to a loading position and for swinging said bowl to raise its rear wall when said bottom member swings from the load carrying to the dumping position.
10. 3. In a scraper, carrying means adapted for travel on the ground, a draft means, a bowl having an open bottom and front, rear and side walls and an arm extending forwardly from its front end, a bottom member in said bowl having a front scraping edge and pivoted to said draft means on a transverse axis and pivoted to said carrying means on an axis parallel to said axis, to swing upwardly at its front edge from a scraping position to, and past a load carrying position, to a rearwardly facing dumping position, means for oscillating said bottom member on its axis, means pivotally supporting said bowl on said bottom member on an axis parallel with said axes, and disposed to raise said bowl bodily when said bottom member swings from a scraping to a dumping position, and means on said draft means having a longitudinal guiding slot, which rises upwardly and rearwardly from its front end and thence downwardly and rearwardly and
15. 40. 45. 50. 55. 60. 65. 70. 75. 5. In a scraper, carrying means adapted for travel on the ground, a draft means, a bowl having an open bottom and front, rear and side walls and having a passage under its front wall for entrance of scraped material, a bottom member in said bowl having a front scraping edge and pivoted on said draft means on a transverse axis and pivoted on said carrying means on an axis parallel with said axis to swing upwardly at its front edge from a scraping to a load carrying position closing said open bottom, and then upwardly to a rearwardly facing dumping position, means for so swinging said bottom member, means pivoting said bowl on said bottom member on an axis parallel with said axes, and means for closing said passage when said bottom member is in the load carrying position and operative to leave said passage open when said bottom member is in the scraping position.

travel on the ground, a draft means, a bowl having an open bottom and front, rear and side walls and having a passage under said front wall for entrance of scraped material, a bottom member in said bowl having a front scraping edge and pivoted on said draft means on a transverse axis and pivoted on said carrying means on an axis parallel with said axis to swing upwardly at its front edge from a scraping to a load carrying position closing said open bottom, and then upwardly to a rearwardly facing dumping position, means for so swinging said bottom member, means pivoting said bowl on said bottom member on an axis parallel with said axes, and means for closing said passage when said bottom member is in the load carrying position and operative to leave said passage open when said bottom member is in the scraping and dumping positions.

6. In a scraper, carrying means adapted for travel on the ground, a draft means, a bowl having an open bottom and front, rear and side walls and having a passage under said front wall for entrance of scraped material, a bottom member in said bowl having a front scraping edge and pivoted on said draft means on a transverse axis and pivoted on said carrying means on an axis parallel with said axis to swing upwardly at its front edge from a scraping to a load carrying position closing said open bottom, and then upwardly to a rearwardly facing dumping position, means for so swinging said bottom member, means pivoting said bowl on said bottom member on an axis parallel with said axes, means for swinging said bowl to raise its front wall when said bottom member swings from the scraping to the load carrying position, and means for closing said passage when said bowl is so swung.

7. In a scraper, carrying means adapted for travel on the ground, a draft means, a bowl having an open bottom and front, rear and side walls and having a passage under said front wall for the entrance of scraped material, a bottom member in said bowl having a front scraping edge and pivoted on said draft means on a transverse axis and pivoted on said carrying means on an axis parallel with said axis to swing upwardly at its front edge from a scraping to a load carrying position closing said open bottom, and then upwardly to a rearwardly facing dumping position, means for so swinging said bottom member, means pivoting said bowl on said bottom member on an axis parallel with said axes, means for swinging said bowl to raise its front wall when said bottom member swings from the scraping to the load carrying position and for raising its rear wall when said bottom member swings from the load carrying to the dumping position, and means for closing said passage when bottom member is in the load carrying position and which leaves said passage open when said bottom member is in the scraping and dumping positions.

8. In a scraper, carrying means adapted for travel on the ground, a draft means, a bowl having an open bottom and front, rear and side walls and having a passage under said front wall for the entrance of scraped material, a bottom member in said bowl having a front scraping edge and pivoted on said draft means on a transverse axis and pivoted on said carrying means on an axis parallel with said axis to swing upwardly at its front edge from a scraping to a load carrying position closing said open bottom, and then upwardly to a rearwardly facing dumping position, means for so swinging said bottom member, means pivoting said bowl to said bottom member

on an axis parallel with said axes, means for swinging said bowl to raise its front wall when said bottom member swings from the scraping to the load carrying position and for raising its rear wall and lowering its front wall when said bottom member swings from the load carrying to the dumping position, a closure for said passage, means pivotally supporting said closure so that it is adapted to swing downwardly by gravity to close said passage, and means supporting said closure in the open position when said bottom member is in the scraping position and which supports said closure in the closed position when said bowl swings to raise its front edge when said bottom member swings from the scraping to the load carrying position.

9. In a scraper, carrying means adapted for travel on the ground, a draft means, a bowl having an open bottom and front, rear and side walls and having under said front wall a passage for the entrance of scraped material, a bottom member in said bowl having a front scraping edge and pivoted on said draft means on a transverse axis and pivoted on said carrying means on an axis parallel to said axis to swing upwardly at its front edge from a scraping to a load carrying position closing said open bottom, and then upwardly to a rearwardly facing dumping position, means for so swinging said bottom member, means pivoting said bowl to said bottom member on an axis parallel with said axes, means for swinging said bowl to raise its front wall when said bottom member swings from a scraping to the load carrying position and for raising its rear wall and lowering its front wall when said bottom member swings from the load carrying to the dumping position, a closure, means pivotally supporting said closure so that it is adapted to swing downwardly by gravity to close said passage, means supporting said closure in the open position when said bottom member is in the scraping position and which supports said closure in the closed position when said bowl swings to raise its front wall, and means supporting said closure in the open position when said bowl swings to raise its rear wall and lower its front wall.

10. In a scraper, carrying means adapted for travel on the ground, a draft means, a bowl having an open bottom and front, rear and side walls, a bottom member in said bowl having a front scraping edge and pivoted on said draft means on a transverse axis and pivoted on said carrying means on an axis parallel with said axis to swing upwardly at its front edge from a scraping to a load carrying position closing said open bottom, and then upwardly to a rearwardly facing dumping position, means pivoting said bowl to said bottom member on an axis parallel with said axes, the lines connecting said axes forming a triangle, said axis on said carrying means being the center around which the other two axes revolve, means connected to said draft means and to said bottom member eccentric to said axis on said carrying means for so swinging said bottom member, and means connecting said bowl with said draft means by which said bowl swings upwardly on its axis to raise its front wall when said bottom member swings from the scraping to the load carrying position and swings upwardly at its rear wall when said bottom member swings from the load carrying to the dumping position.

11. In a scraper, carrying means adapted for travel on the ground, a draft means, a bowl having an open bottom and front, rear and side

walls, a bottom member in said bowl having a front scraping edge and pivoted on said draft means on a transverse axis and pivoted on said carrying means on another transverse axis to swing upwardly at its front edge from a scraping to a load carrying position closing said open bottom, and then upwardly to a rearwardly facing dumping position, means connecting said bottom member to said draft means for so swinging said bottom member, means pivoting said bowl to said bottom member on an axis parallel

5 with said axes, and means connecting said bowl with said draft means by which said bowl will be swung on its axes to raise its front wall when said bottom member swings from the scraping to the load carrying position, and will be swung to raise its rear wall when said bottom member swings from the load carrying to the dumping position.

ALBERT R. HENRY.
MARION C. WILLS.
